UNITED STATES PATENT OFFICE.

ALEXANDER M. HAUBRICH, OF CHICAGO, ILLINOIS, ASSIGNOR TO THE STROMBERG-CARLSON TELEPHONE MANUFACTURING COMPANY, OF ROCHESTER, NEW YORK, A CORPORATION OF NEW YORK.

SWITCHBOARD.

1,356,622.

Specification of Letters Patent. Patented Oct. 26, 1920.

Application filed August 13, 1917. Serial No. 185,859.

To all whom it may concern:

Be it known that I, ALEXANDER M. HAUBRICH, a citizen of the United States, residing at Chicago, in the county of Cook and State of Illinois, have invented a certain new and useful Improvement in Switchboards, of which the following is a full, clear, concise, and exact description, reference being had to the accompanying drawings, forming a part of this specification.

My invention relates to switchboards and particularly to telephone switchboards, and its object is to provide an improved means for at all times indicating to the attendants of an exchange switchboard the condition of lines or the stations thereof. In my prior Patent No. 828,848, I set forth a means for accomplishing the aforesaid object. The present invention is an improvement over the disclosure of my former patent as will be apparent from the description thereof which follows.

It has heretofore been the custom to mark the face of the switchboard adjacent to the line terminal jacks thereof in a characteristic manner by pins having different colored heads, or by depressions filled with paints of different colors, each color corresponding to a certain operative condition of the line or substation, or instrument connected to the line; this being a particularly useful practice in connection with party lines to indicate the particular stations which are connected to the line and their condition.

In my present invention I provide means preferably constructed of pieces of celluloid differently colored, and adaptable to be fastened to the face of the switchboard by pins projecting through each group of the line jack designations, the pieces being preferably fastened to the face of the switchboard by a single double pointed tack. In this way I am enabled to apply designations to jacks placed very closely together in the switchboard, and at the same time eliminating the drilling of many small holes in the switchboard which weakens the structure of the jack strips.

This is especially desirable, since in large cities modern manual switchboards have been constructed having a very large number of telephone lines connected thereto, and in which the number of multiple jacks is very great. Naturally in order that each

operator may be able to reach one of the multiple jacks belonging to each of the telephone lines, the jacks have necessarily had to be constructed very small and to be placed very closely together. This practice has continued to such a point that the space between the jacks has become very restricted, so much so, that the indicating means of the art such as illustrated in my former patent, whereby the operator may at a glance ascertain whether or not the called subscriber is obtainable, and to indicate to the operator whether the called line was out of service or the instrument at the substation defective, or to advise the operator as to the parties connected to the said line, has been found difficult of application, so much so that either the indicating means have been in some cases eliminated, or the use of the same restricted. But where the advantages of the indicating means have been retained the jack strips have been so weakened by the necessary drilling that strength and rigidity have been sacrificed and breakages, etc. multiplied.

In other cases the switchboards have of necessity been made much larger than would otherwise need to be the case, and the number of lines which a single operator may have access to through multiple jack connections has been very much decreased, and in some of these cases it has been necessary to establish a supplemental "B" board to which calls are trunked instead of making the connection directly at the main switchboard. By my invention I am enabled to increase the size of the indicating means, at the same time permitting the decrease in space between the jacks, thereby creating a better operating condition, as well as a saving of expense for operating, and initial cost, and maintenance of the switchboard. The accompanying drawings will more clearly illustrate my invention in which

Figure 1 shows a front view of a section of jack banks. Fig. 2 shows a front view enlarged, of one of the jack strips. Fig. 3 is an enlarged sectional view through the front support of a jack bank, taken on line A—A of Fig. 2. In Fig. 4 are shown the different indicating means preferably shaped and L shaped which may be secured to the face of the switchboard in my improved structure. Also Fig. 4 shows a side

view of the double pointed tack or staple which secures the superposed indicating means together and to the face of the switchboard. It is obvious that the jack banks 5 may be of any structure, and the indicating means may be of varying shapes.

I provide as shown in Figs. 1 and 3, a series of apertures or drill holes *a*, a pair of which are placed between adjacent jacks, 10 the drilling occurring on a line drawn perpendicular to the jack strips and midway between adjacent jacks, and each aperture being placed thereon at points approximately midway between the edges of the 15 jack strips and the edges of adjacent jacks, thus providing the greatest amount of supporting material about the said apertures, and weakening the jack strips the minimum amount possible. The body of jack strips 20 is commonly made of hard rubber or other insulating material to insulate the thimbles of the jacks one from the other, and such material being somewhat weak, it is important that the drilling be thus restricted, as 25 much as possible. The staples are preferably constructed of round wire suitably bent as illustrated so that they may be removed readily from the switchboard. The jack designations as illustrated in Fig. 4 can 30 be made of celluloid or enameled metal, preferably the former, and suitably colored to convey indications of different line conditions to the operator.

In Fig. 1 between the fourth and fifth 35 jacks in the top strip, I have shown the indicating means of my invention arranged with a pair of indicators for the fourth jack, and a pair of indicators for the fifth jack all fastened together by the common means 40 consisting of the double pointed tack or staple. This may indicate to the operator, for example, that the line connected to the fourth jack is a party line having stations 45 #3 and #4 thereon. Also that the line connected to jack 5 is a party line having stations #1 and #2 thereon.

In Fig. 2, I show the same arrangement 50 of indicators between jacks 6 and 7, and also to the right of jack 7 between jack 7 and jack 8, I show additional indicators indicating in combination with the indicating means to the left of the jack that the jack 7 is connected to a party line having four parties thereon.

55 Jack 8 of Fig. 2 is shown covered by the indicator fastened by the staple *t*₂ placed between jack 8 and jack 9, the latter not being shown, the said indicating means being of the proper size and shape to entirely 60 cover the aperture of jack 8, so that the operator's switchboard plug cannot gain access thereto. The obvious indication to the operator is that such a line has no telephone connected thereto, and the color of 65 the indicating means may be such as to in-

dicate to the operator whether such a party's telephone has been removed, or whether the line has been connected to a jack having a different number. In such a latter case, on the face of this indicator D 70 may be printed the number of the jack to which the party's telephone is now connected. This indicating means is D shaped and may be reversed to cover a jack to the left of the securing staple as shown in Fig. 75 2 at jack 8 just described, or it may be turned around to cover a jack to the right thereof as may be desired. A pair of such indicating means may be secured by a common staple, the one extending to the right 80 and the other to the left for adjacent jack indications.

Again referring to Fig. 4, such indicating means as illustrated at L may be combined with the indicating means as shown at D, 85 either of which is capable of the reversal, and thus to supply indications to jacks on either side of the securing means as T. The indicating means may be suitably colored to indicate whether the instruments are serv- 90 iceable or have been removed for repairs, and also may supply other indications of widely varying character.

I am aware that the forms and colors of the indicating means may be varied from 95 the above described and illustrated embodiment of my invention, and also that the securing means may be varied, such as for instance, by replacing the single double pointed tack illustrated and described to 100 single tacks or pins without departing from my invention in its entirety. The forms illustrated and described being however, I think preferable for the purpose, though some of the advantages thereof may be obtained by using the same in part rather than in toto, but what I claim as my invention is:—

1. In a telephone exchange switchboard, the combination with a plurality of switchboard jacks, a supporting insulating strip therefor, a flat indicator adapted to be secured to the said insulating material between a pair of adjacent jacks and having a portion extending in proximity to one of 115 the said jacks to indicate an operative condition of a telephone line connected to the said jack.

2. In a telephone switchboard, the combination with a plurality of telephone line 120 switchboard jacks arranged in strips, of openings therefor in the face of the switchboard, a plurality of indicating means secured between adjacent openings of a strip, and common securing means for the said indicating means.

3. In a telephone switchboard, the combination with adjacent telephone line jack 125 openings arranged in strips in the face thereof, of a plurality of indicating means 130

for each of the said openings secured to said strip, and common securing means for the said indicating means.

4. In a telephone switchboard, the combination with an insulating face therefor, of a pair of adjacent line jack openings therein, of an L shaped indicating means for each of the said openings, and common securing means for the said L shaped means to secure the last-named means to the insulating face of the switchboard.

5. In a telephone switchboard, the combination with an insulating face therefor, of a plurality of jack openings therein, of indicating means for the said openings extending from between the openings to points over a portion of the openings, and common securing means for the indicating means of adjacent openings.

6. In a telephone switchboard, the combination with an insulating face therefor, of a jack opening therein, of an L shaped indicating means for the said opening, securing means to fasten the said indicating means to the face of the switchboard to the left or to the right of the said opening, the said indicating means being reversible to have an arm thereof extending to the right or to the left to a point adjacent to said opening.

7. In a telephone switchboard, the combination with an insulating face therefor, of line jack openings therein, of an L shaped semaphore adapted to be placed between a pair of the said openings, one arm of the said semaphore extending above or below a portion of the opening located on one side or the other on the said semaphore, securing means located between the said openings to secure the said semaphore to the face of the switchboard, said semaphore by its position above or below its associated jack opening indicating a particular condition of the line associated therewith.

8. In a telephone switchboard, the combination with a strip of telephone line jacks therefor, having a common face, openings in the said face for the said jacks, a plurality of flat indicating means for the said openings, and common securing means for indicating means for a pair of openings to secure the said indicating means to the face of said strips.

9. In a telephone switchboard, the com-

bination with a strip of telephone line jacks 55 therefor having a common face, openings in the said face for the said jacks, a plurality of flat indicating means for the said openings, and U shaped securing means for indicating means for a pair of openings 60 to secure the said indicating means to the face of the switchboard.

10. In a telephone switchboard, the combination with a strip of telephone line jacks therefor having a common face, openings 65 in the said face for the said jacks, a plurality of L shaped indicating means for the said openings, and U shaped securing means for indicating means for a pair of openings to 70 secure the said indicating means to the face of the switchboard.

11. In a telephone switchboard, the combination with a face therefor, of openings in the said face for telephone line jacks, flat indicating means for one of the said 75 openings extending across the said opening, and securing means for the said indicating means located to one side of the opening.

12. In a telephone switchboard, the combination of a jack bank, jack openings 80 therein, a set of two semaphores between each pair of jack openings, flat indicating means for the said openings, and double pointed tacks the prongs of which are adaptable for insertion in the said sets of 85 apertures to secure the said indicating means to the jack bank.

13. In a telephone switchboard, the combination of a jack bank, jack openings 90 therein, a set of two semaphores between 90 each pair of jack openings, flat indicating means for the said openings, and double pointed tacks the prongs of which are adaptable for insertion in the said sets of 95 apertures to secure the said indicating means to the jack bank, the said indicating means being adaptable for interchangeable association with different openings to the right or left of the securing tacks by reversal of the said indicating means. 100

In witness whereof I hereunto subscribe my name this eighth day of August, A. D. 1917.

ALEXANDER M. HAUBRICH.
